(57) CLAIM

The ornamental design for a sports bra with sleeves, as shown and described.

DESCRIPTION

FIG. 1 is a top perspective view of a sports bra with sleeves showing our new design;

FIG. 2 is a front view thereof;

FIG. 3 is a rear view thereof;

FIG. 4 is a side view thereof;

FIG. 5 is a another side view thereof;

FIG. 6 is a top view with the sleeves extended outward thereof; and,

FIG. 7 is a top view with the sleeve extended upward thereof.

The broken lines shown in the drawings represent stitching in the fabric and form part of the claimed design.
